GOLF CLUB HEAD

Ernest R. Andis, 3528 N. Bay Drive, Racine, Wis.

Filed Oct. 5, 1965, Ser. No. 87,327

Term of patent 14 years

(Cl. D34—5)

FIGURE 1 is a perspective view of a golf club head embodying my new design and taken generally from above to the side and from one end thereof;

FIGURE 2 is another perspective view of the head shown in FIGURE 1 but on an enlarged scale and taken generally from above and from the opposite side and end than that shown in FIGURE 1;

FIGURE 3 is a perspective view of the head shown in FIGURE 2 but taken generally from the other end thereof;

FIGURE 4 is a plan view of the head;

FIGURE 5 is a side elevational view;

FIGURE 6 is an end elevational view;

FIGURE 7 is a bottom view of the head.

The broken lines indicating a shaft in FIGURE 1 are for illustrative purposes only.

I claim:

The ornamental design for a golf club head, substantially as shown and described.
